UNITED STATES PATENT OFFICE

JOHN J. LYTH, OF VALLEYFIELD, QUEBEC, CANADA

STENTER CLIP

Application filed January 26, 1929. Serial No. 335,363.

This invention relates to improvements in stentering machine clips, and the primary object of the invention is to provide a clip which will remain open during movement 5 from the discharge end of the machine to the charging end for the purpose of eliminating wear of the faller teeth and of the table.

A further object is to provide a simple, durable and inexpensive clip composed of few 10 parts positively operated with a small expenditure of power and without reliance on springs.

A still further object is to provide an arrangement such that the clamping capacity 15 is the greatest possible for the size of the faller.

Another object is to guard the feeler and the fabric on the table against soiling by contact with oily lint detached from the driving sprockets and also to prevent accumulations of lint from interfering with the operation of the feeler.

Various other objects and the advantages 20 of the invention may be ascertained from the following description.

Each clip forms or is mounted on one link of a stenter chain in the usual manner. The clip body comprises a bottom plate above which the slotted clamping table is mounted. 25 Rising from the table is a pair of arms to which the faller and the opener are pivoted, the faller having a cam slot in which the opener engages to positively operate the faller. The feeler is carried by the faller and 30 directly holds the faller out of contact with cloth on the table until the feeler slots in the table are uncovered. The direct relation of the feeler and faller also causes the faller to positively press the feeler down on cloth 35 on the table.

In the accompanying drawings, which illustrate the preferred embodiment of the invention but to the details of which the invention is not confined, since modifications and substitutions may be made:

Fig. 1 is a side elevation of the clip open.

Fig. 2 is a side elevation of the clip partly closed and feeling for a proper positioning 40 of cloth.

Fig. 3 is a side elevation of the clip fully closed and in cloth gripping position.

Fig. 4 is a front elevation of the clip fully open.

Fig. 5 is a plan view of the clip fully open.

Fig. 6 is a plan view of the feeler.

Referring more particularly to the drawings, 11 designates a chain link portion proper having at one end a pair of vertically spaced apertured jaws 12 and at the other 15 end an apertured tongue 13 adapted to be pivotally connected between the jaws of an adjoining link. Between the jaws and the tongue the link is formed with an aperture 14 for reception of the teeth of the sprocket 20 wheels (not shown), which move the chain formed by the connected links.

Mounted upon the link 11 is the solid bottom plate 15 of the clip, from the forward edge of which there projects a pair of arms 16 united at their outer ends by a longitudinal member 17. The clip table 18, which forms the lower jaw of the cloth clamp is rigidly secured to the parts 15, 16 and 17 and is provided with one or more transverse slots 19 for passage of a feeler. A pair of side plates 20 project upwardly from the bottom plate and forwardly over and beyond the front edge of the table. A rib 21 also extends upwardly from the bottom plate 25 between the side plates.

A faller 22 of any usual or suitable pattern, having cloth gripping teeth 23 is pivotally mounted at its upper end to the forward extremities of the side plates by means of a pin 24. The faller is, as usual, of such dimensions that when lowered into contact with the table it inclines inwardly or rearwardly, as shown in Figure 3, so that the pull of the cloth will increase the gripping effect. Between the side plates, the faller is provided with a rearwardly extending arm 25 formed with a slot 26. The slot is enlarged at its forward end and opens at the rear end of the arm and is formed on its upper side with an approximately V-shaped notch or recess 27. It will be noted that the entire weight of the faller, including the arm, is to the rear of the pivot 24 so that the

faller is constantly urged to downward movement by the action of gravity.

A feeler 28 is pivotally mounted on the faller arm toward the rear end thereof and below the slot by means of a pin 29. This feeler preferably embraces the faller arm and includes a pair of arms 30, one on each side of the faller arm, extending forwardly from the pivot and adapted to pass downwardly through the table slots. The opposite end of the feeler projects rearwardly of the pivot and is of such weight that the feeler, when free, will hang in approximately horizontal position, as shown in Figure 1. The rearward end of the feeler is adapted to engage the table in rear of the slots 19, as shown in Figure 2. The body of the feeler is adapted to engage two stops 31 and 32 formed on the lower edge of the faller arm for the purpose of limiting the swing or oscillation of the feeler about its pivotal centre and preventing the feeler assuming or being accidentally forced into an inoperative relation to other parts of the clip.

An opener and closer 33 (for convenience termed "opener") is pivoted at its lower end between the side plates by means of a pin 34. The lower portion of the opener may be bifurcated for lightness and strength and to extend the base thereof in the longitudinal direction of the clip, so as to effectively resist longitudinal displacement upon engagement with opening and closing cams 35 and 36 respectively. The opener is provided with a pair of forwardly extending arms 37 adapted to embrace between them the faller arm 25. An antifriction roller 38 is mounted between the forward ends of the opener arms and is of a size to travel easily in the faller slot 26 and to fit snugly into the notch 27 and also to fit very loosely in the enlarged forward end of the slot. The opener is provided with rearwardly extending lugs 39 below the pivot 34 adapted to engage the bottom plate to limit rearward swing of the opener to an amount less than would cause disengagement of the roller 38 from the faller slot. The top of the rib 21 may, if desired, serve to limit forward swing of the opener to such extent that the roller is cut off contact with the faller slot edges when the faller is lowered so as to relieve the faller of the weight of the opener, but this arrangement may be otherwise. Spaced beneath the table, a plate 40 extends forwardly between the arms 16 to a distance beyond the ends of the feeler arms.

The operation of the device is as follows:—At the charging end of the stentering machine the clips are open as shown in Figure 1, and the selvedge of cloth is fed onto the table of each clip as it comes to the charging point. The clip, moving at the same speed as the cloth, comes to a stationary closing cam 36 which engages the opener 33 to

tip the same forwardly from the upright position shown in Figure 1 sufficiently to drive the roller 38 out of the notch 27 and toward the front end of the slot 26. This movement of the opener overbalances it, so that it tends to fall forward by gravity until stopped by the rib 21. In the initial movement of the opener, expulsion of the roller from the notch first slightly raises the faller and then, when the roller is out of the notch, permits the faller to fall with the opener until the feeler 28 is lowered into contact with cloth on the table. The relative positions of the parts are now as shown in Figure 2 and it is to be noted that, whereas the feeler arms 30 are spaced above the table a distance representing the thickness of the cloth, the opposite end of the feeler housed between the side plates 20 is in contact with the table and the whole feeler is pressed downwardly by the weight of the faller (and, if the fitting of the rib stop 21 permits, is also pressed down by the weight of the opener bearing on the bottom of the faller slot). This supporting of the feeler by the table and by the cloth holds the feeler against swinging about its pivot and also holds the faller up sufficiently for the cloth to slip easily between the table and the faller teeth 23. The clip moves at an angle to the edge of the cloth in the well known manner, so as to draw away from the cloth and finally disengage the feeler from the cloth. As soon as this disengagement occurs the feeler swings downwardly about its point of support on the table, the arms passing through the table slots 19, and thus lowers its point of pivotal connection with the faller, so that the faller also drops to clamp the cloth down on the table. The positions of the parts are now as shown in Figure 3. In the movement of the feeler reliance is not placed solely on the weight of the feeler but its movement is assured by reason of the downward pressure of the faller and perhaps, also, of the opener. In the clamping position shown in Figure 3 there must be clearance between the roller 38 and the top of the faller slot 26, but the fitting of the rib 21 may be such that the opener will advance farther than shown, so as to press downwardly on the faller. In the final position the rear end of the feeler may be still in contact with the table or may be slightly raised above it, as shown in Figure 3. Fitting of the stop 32 should be such as to permit the feeler a little play in this position, so as to ensure against it supporting any part of the weight of the faller and thus interfering with the clamping action.

At the discharge end of the machine, the front of the opener 33 comes into contact with a stationary opening cam 35 which swings the opener rearwardly from the position of Figure 3 to the position of Figure 1 and causes it to raise the faller and to position

the roller 38 in the notch 27, so as to hold the faller in raised position. The opening movement is quite sudden, especially in machines operating at high speed, and might cause the 5 opener to overbalance rearwardly and disengage from the faller were it not for the stops 39 which engage the plate 15 and prevent this. The rib 21 checks excessive forward movement of the opener, such as would

10 result in thrusting the feeler too forcibly against cloth and driving the cloth through the table slots. As the faller arm rises, it of course carries with it the feeler which is so balanced that it tends to hang horizontally 15 with the ends of its arms above the lower end of the faller, so that cloth entering the clip cannot get over the feeler arms but must pass under them.

Mounting of the feeler on the faller possesses the advantage, as compared with other types of clips that the paths of the feeler and faller do not intersect and necessitate cutting away the lower edge of the faller to permit movement of the feeler to position above the 20 lower end of the faller. This enables the full length of the faller to be available for cloth gripping.

The clip operates positively or by gravity and entirely without use of springs. If the 25 action of the faller should be sluggish, the opener gives a definite downward thrust to the faller and moves the feeler positively into contact with cloth on the table. If the feeler is sluggish the downward pressure of the faller ensures feeler operation.

The plate 40 prevents accumulations of lint and grease worked forward by the sprocket teeth engaging in the opening 14 of the link from coming in contact with the feeler and 30 being thereby transferred to the cloth.

In its open position the opener tends to overbalance rearwardly so that vibration will not tend to release the faller, so that the clip remains open during its return from the 35 discharge end of the machine to the charging end and in this way prevents the teeth 23 and table from wearing one another by chattering.

As there are no springs to be overcome, the 40 amount of power required to open the clip is less than usual and the amount of power required to close the clip is still less.

Having thus described my invention, what I claim is:—

55 1. In a stentering machine clip, a body; a faller pivoted to said body including a rearwardly projecting arm having a slot therein notched in its upper edge; and an opener pivoted to said body engaged in the aforesaid slot to raise said faller and to releasably lock the faller in raised position.

2. In a stentering machine clip, a body; a faller pivoted to said body including a rearwardly projecting arm having a slot therein 60 notched in its upper edge; and an opener piv-

oted to said body engaged in the aforesaid slot to raise said faller and to releasably lock the faller in raised position, the faller and opener being so formed and disposed that in the open position of the clip the opener is over-balanced and tends to movement in faller lifting direction, while the faller is constantly urged by gravity to maintain engagement of the opener in the faller notch. 70

3. In a stentering machine clip, a body, a faller pivoted to the body, an opener pivoted to the body, arms rigidly connected respectively to the faller and to the opener and slidably engaging one another, and gravity actuated latching means on said arms automatically operable upon opening of the clip to releasably lock the clip by reason of the tendency of the opener and faller to return to closed position in full open position. 75

4. In a stentering machine clip, a body, a faller pivoted to the body, an opener pivoted to the body, and latching means connected to the faller and to the opener automatically operable by relative movement of the faller and opener upon opening of the clip to releasably lock the faller and the opener in their full open positions. 80

5. In a stentering machine clip, a body, a faller pivoted to the body, an opener pivoted to the body, and means operating automatically by relative movement of the faller and opener upon raising of the faller and opener for releasably latching the faller and opener together and against movement from their raised positions, whereby the clip is releasably locked in full open position. 85

6. In a stentering machine clip, a body, a faller pivoted to the body and an opener pivoted to the body, said faller and opener including parts adapted to move in intersecting paths downwardly and toward one another during closing of the clip, one of said parts including a cam surface against which the other part leans by gravity in the open position of the clip with tendency to lift said cam surfaced part, inferior in amount to the gravitational opposition of the cam surfaced part to such lifting, whereby the parts are releasably locked in full open position. 90

7. In a stentering machine clip, a body, a faller pivoted to the body, an opener pivoted to the body, and latching means connected to the faller and to the opener operable by the tendency of the faller and opener to return to closed position to releasably lock the faller and the opener in their full open positions. 105

8. A stentering machine clip comprising, a body including a table forming one jaw of the clip, a faller pivoted to the body above the table forming the other jaw of the clip, an opener pivoted to the body at approximately the level of and in rear of the table, a slotted arm projecting rearwardly from the faller, and an arm projecting forwardly 110

from the opener operatively engaging in the slot of the faller arm to raise the faller.

9. In combination with a device according to claim 8, stops on the body to limit movement of the opener and prevent disengagement of the faller and opener arms.

10. A device according to claim 8, in which the faller arm is provided with a notch extending upwardly from the slot and in which 10 the opener arm is adapted for engagement in said notch to releasably lock the faller and opener in their raised positions.

11. In a stentering machine clip, a body, a faller pivoted to the body and adapted to 15 be moved to cloth holding position by gravity, an opener pivoted to the body engaging the faller and adapted to be moved by gravity with positive faller depressing effect, said faller and opener being adapted for direct 20 interlocking and to be retained in interlocked relation solely by gravity to hold the clip in full open position during transit from the discharging to the charging end of a stentering machine.

25 12. In a stentering machine clip, a body, a faller pivoted to the body at the front thereof and projecting rearwardly from its point of pivotal attachment, an opener pivoted to the body in rear of the pivotal attachment 30 of the faller and projecting forwardly from its point of pivotal attachment into engaging relation with the faller, the engageable portions of said opener and faller being formed for latching engagement with one 35 another in the open position of the clip to releasably lock the clip by reason of the tendency of the opener and faller to return to closed position in open position.

40 13. In a stentering machine clip, a body, a faller pivoted to the body, an opener pivoted to the body and entirely disconnected from the faller, said opener being engageable with the faller to raise and lower the same and solely by itself to releasably lock the faller 45 in elevated position.

46 14. A stentering machine clip comprising a body including a lower cloth supporting jaw, an upper jaw member pivoted to the body and adapted to descend upon said lower 50 jaw to clamp cloth thereto, and an opener pivoted to the body engaging said upper jaw member and adapted to raise the upper jaw member and to releasably latch the upper jaw member in its raised position, said latching 55 being effected solely by the interengagement of the upper jaw member and the opener and without the agency of any third member.

60 15. A stentering machine clip comprising a body including a lower cloth supporting jaw, an upper jaw member pivoted to the body and adapted to descend by gravity upon said lower jaw to clamp cloth thereto, and an opener pivoted to the body engaging 65 said upper jaw member and adapted to de-

scend by gravity with capacity to lower the upper jaw, said opener being also adapted to raise the upper jaw and to releasably latch the upper jaw in its raised position, said latching being effected by the force of gravity acting through the interengagement of the upper jaw member and the opener and without the agency of any third member, said upper jaw member being releasable for descent by movement imparted to the opener 70 to move the same out of latching engagement with the upper jaw member.

75 16. A stentering machine clip according to claim 14, in which the upper jaw member includes a jaw lifting arm formed in its lower edge with a notch into which the opener enters with latching effect.

80 17. A stentering machine clip according to claim 15, in which the upper jaw member includes a jaw lifting arm formed with a slot 85 and a notch in the upper edge of the slot, the opener being engageable with the upper edge of the slot for jaw lifting and with the lower edge of the slot for jaw lowering and being engageable in the notch with latching effect.

85 18. A stentering machine clip according to claim 15, in which the upper jaw member includes a jaw lifting arm formed with a slot and a notch in the upper edge of the slot, the opener being engageable with the upper edge of the slot for jaw lifting and with the lower edge of the slot for jaw lowering and being engageable in the notch with latching effect, in combination with a pair 90 of opener actuating elements positioned to positively move the opener in opposite directions for clip opening and clip closing respectively.

95 19. A stentering machine clip comprising a body including a lower cloth supporting jaw, an upper jaw member pivoted to the body and adapted to descend by gravity upon the lower jaw to clamp cloth thereto, and an 100 opener member pivoted to the body and engaging said upper jaw member, the surface of one of said members in engagement with the other member in the raised position of the members being so inclined relatively to the path followed by the engaged portion of the other member about its pivotal point that the force of gravity acting in one member is opposed to the force of gravity acting in the other member whereby the members are releasably held in raised position.

110 20. A stentering machine clip comprising a body including a lower cloth supporting jaw, an upper jaw member pivoted to the body and adapted to descend by gravity upon the lower jaw to clamp cloth thereto, and an 115 opener member pivoted to the body and engaging said upper jaw member, the surface of the jaw member in engagement with the opener member in the raised position of the members being so inclined relatively to the 120

path followed by the engaged portion of the 5
opener member about its pivotal point that downward movement of the opener member from its raised position would further raise the jaw member against the action of gravity, the gravitational effect in the jaw member being sufficient to overcome said raising action, whereby the members mutually support one another in raised position.

10 21. A stentering machine clip comprising a body including a lower cloth supporting jaw, an upper jaw member pivoted to the body and adapted to descend by gravity upon the lower jaw to clamp cloth thereto, and an 15 opener member pivoted to the body and engaging said upper jaw member, the surface of the jaw member in engagement with the opener member in the raised position of the members being so inclined relatively to the 20 path followed by the engaged portion of the opener member about its pivotal point that downward movement of the opener member from its raised position would further raise the jaw member against the action of gravity, the gravitational effect in the jaw member being superior to the gravitational effect 25 in the opener whereby the jaw member tends to further raise the opener, and means limiting the upward movement of the opener 30 whereby the members are releasably locked in raised position.

22. A stentering machine clip comprising a body, a faller pivoted to the body, an opener pivoted to the body, said faller and opener 35 being provided with mutually engaging means for transmitting movement from one to the other and tending to return by gravity from their open positions to their closed positions, the said mutually engaging means being operable in the open positions of the 40 opener and faller and by reason of the tendency of the opener and faller to return to their closed positions to releasably lock the opener and faller in their full open positions.

45 23. In a stentering machine clip, in combination, a body; a faller pivoted to the body; and an opener for said faller pivoted to said body and engaged by said faller, and adapted to be so balanced in its open position that 50 the force of gravity tends to swing the opener in its entirety about its pivotal axis away from said faller.

24. In a stentering machine clip, in combination, a body; a faller pivoted to the body; and an opener for said faller engaging and adapted to impart cloth gripping motion thereto, so formed and co-related with respect to said faller that in its open position the force of gravity tends to swing the same in its 60 entirety away from said faller and hold the latter component in elevated position.

25. In a stentering machine clip, in combination, a body; a faller pivoted to said body; and an opener for said faller pivoted to said 65 body, said faller and opener being so formed

and co-related that gravitational force acting on said faller and opener is restrained, independently of associated means other than the means limiting movement of said opener, in such wise that the faller is retained in 70 either open or closed position solely by said opener.

In witness whereof, I have hereunto set my hand.
